UNITED STATES PATENT OFFICE

ALFRED B. BELL, OF PHILADELPHIA, PENNSYLVANIA, ASSIGNOR TO HALE & KILBURN CO., OF PHILADELPHIA, PENNSYLVANIA, A CORPORATION OF DELAWARE

LOCKING DEVICE FOR CAR SEATS

Application filed February 24, 1930. Serial No. 430,572.

This invention relates to locking device for car seats, and the principal object of this invention is to provide a latch mechanism of simple, durable and easy operable construction, and adapted to be conveniently associated with rotatable chairs of various types to hold the chairs against rotation until released for rotation by an authorized person using a certain and predetermined type of implement.

A further object of this invention is to provide latch means for rotatable chairs, which requires the application and manipulation of an implement of a certain type in order to release the mechanism, the mechanism being arranged, however, to automatically engage and lock the seat automatically as the seat arrives in its final position of rotation.

Other objects of this invention will be in part obvious and in part pointed out hereinafter.

In accordance with this invention, the latch means preferably include a plunger wholly concealed within the seat structure so as to be inaccessible to direct manipulation, and adapted to engage suitable keeper recesses provided therefor on another part of the seat structure. The plunger is adapted to be raised to release the seat for rotation by means of a key or other implement, which is adapted to be inserted in a suitable hole in the seat structure and into engagement with the plunger. Preferably, resilient means are provided for causing the plunger to enter a keeper recess automatically whenever the plunger comes into alignment therewith. Preferably, the operating key is removable so that it may be kept in the possession of the authorized operator and thereby prevent the seat being rotated by unauthorized persons and at inopportune times.

In order that a clearer understanding of this invention may be had, attention is hereby directed to the accompanying drawings forming a part of this application, and illustrating certain possible embodiments of this invention.

Referring to the drawings, Fig. 1 is a rear perspective view of a portion of a rotating

seat, in which the present invention may be embodied;

Fig. 2 is a sectional view thereof and is taken on the line 2—2 of Fig. 1;

Fig. 3 is a sectional view of the same and is taken on the line 3—3 of Fig. 2; and

Fig. 4 is an enlarged sectional view of a detail of the construction and is taken on the line 4—4 of Fig. 3.

Similar reference characters refer to similar parts throughout the several views of the drawings.

Referring to the drawings, for the purpose of presenting an illustration of one possible embodiment of my invention, I have shown in the drawings a rotating chair, comprising in the drawings a rotating chair, comprising a suitable base or pedestal 1, on which a suitable seat back and cushion unit 2 is rotatably mounted. In the chair illustrated, the seat back and cushion unit is also adapted to automatically shift on the pedestal whenever it is rotated thereon.

On the pedestal 1 is positioned a plate or casting 3, provided with shoulders or flanges 4, forming a curved trackway 5. The seat back and cushion unit 2 is mounted on a block 6 which has a stud 7 seating in the trackway 5. Block 6 is held for rotation and sliding movement on plate 3 by means of gibbs 8, which are secured to plate 3 and have flanges 9 seated beneath plate 3 and flanges 10, overlapping shoulders 11 on block 6.

A suitable housing portion 12 is formed on block 6 to slidably retain a vertical plunger 13. A spring 14, surrounding the pin 13 and seated in the housing portion 12, bears at its upper end against the housing and at its lower end against a collar or sleeve 15, mounted on the lower end of plunger 13. Downward movement of plunger 13 is limited by means of a washer 16 secured to the top of the plunger beneath its head 17.

A portion of the plunger 13 is corrugated, as at 18. A key 19 is provided having a feathered end 20, which may be inserted into a suitable aperture 21 provided by the housing portion 12 into engagement with the corrugations 18, so that when the key 19 is turned in the proper direction, the plunger 13 is elevated.

Suitable keeper recesses are provided on plate 3 for the end of the plunger 13. If desired, the ends of the trackway 5 may constitute such keeper recesses. Also, if desired, a raised surface, such as 22, may be provided on plate 3 so shaped and positioned that the end of the plunger 13 will ride on this member as the seat is being revolved.

The operation is as follows:—When it is desired to reverse the seat, the operator inserts the key 19 into the aperture 21 and engages the key with the plunger. Then by turning the key 19, the plunger is raised out of engagement with the plate 3 and the seat may be rotated. When the plunger comes into alignment with the opposite end of the trackway 5, spring 14 causes the plunger 13 to seat in this recess and the seat becomes locked automatically against rotation until the plunger is again raised by the proper manipulation of key 19.

Obviously, latch mechanism constructed in accordance with the above invention may be incorporated in chairs and seats of various different types. Also, it is readily apparent that the location of the plunger and the location and form of the keeper recesses may be varied considerably.

The latch mechanism is extremely simple and durable, and is of such nature that it prevents rotation of the seat by unauthorized persons who do not have possession of the key, which is required to be used to effect the release of the latch.

As many changes could be made in the above construction and as many apparently widely different embodiments of this invention could be made without departing from the scope thereof, it is to be understood that all matter contained in the above description or shown in the accompanying drawings shall be interpreted as illustrative and not in a limiting sense.

What I claim is:—

1. In a rotatable seat, in combination, a support, a seat frame rotatably mounted on the support, and a vertical latch bolt housed for reciprocation in the seat frame, said support having a recess adapted to receive the bolt to prevent rotation of said frame on the support, said bolt having a key engageable portion and said seat frame having an aperture through which a key may be engaged with the bolt and the bolt disengaged from said recess to permit rotation of the seat frame on the support, and means on the support engaging beneath the bolt and maintaining the bolt retracted while the bolt is out of locking alignment with a recess therefor on the support.

2. In a rotatable seat, in combination, a support, a plate thereon having recesses, a slide-block rotatably supported on the plate and having a boss provided with a vertical passage adapted to align separately with said

recesses and having a horizontal passage extending from the outside of the boss to said vertical passage, and a latch-bolt slidably housed in said vertical passage and adapted to lock into said recesses of the plate when aligning therewith and having a key engageable portion exposed at said horizontal passage, whereby said bolt may be retracted by means of a key inserted in said horizontal passage and engaged with the key engageable portion of the bolt.

3. In a rotatable seat, in combination, a support, a plate thereon having recesses, a slide-block rotatably supported on the plate and having a boss provided with a vertical passage adapted to align separately with said recesses and having a horizontal passage extending from the outside of the boss to said vertical passage, a latch-bolt slidably housed in said vertical passage and adapted to lock into said recesses of the plate when aligning therewith and having a key engageable portion exposed at said horizontal passage, whereby said bolt may be retracted by means of a key inserted in said horizontal passage and engaged with the key engageable portion of the bolt, and means on the upper end of the bolt and engageable against the top of the boss, limiting downward movement of the bolt in the boss.

This specification signed this 20th day of February, 1930.
